(Cl. D54—13)

To all whom it may concern:

Be it known that I, Harold W. Darr, a citizen of the United States, residing at Minneapolis, in the county of Hennepin and State of Minnesota, have invented a new, original, and ornamental Design for a Portable Tire Spreader, of which the following is a specification, reference being had to the accompanying drawing, forming part thereof.

Referring to the drawing:

Fig. 1 is a top plan view of a portable tire spreader showing my novel design;

Fig. 2 is a side elevational view;

Fig. 3 is a rear elevational view; and

Fig. 4 is a front elevational view thereof.

I claim:

The ornamental design for a portable tire spreader, substantially as shown.

HAROLD W. DARR.
